UNITED STATES PATENT OFFICE

155,731

DESIGN FOR A SERVING BAR TOP

Alan J. Ragunt, Rockford, Ill.

Application October 28, 1946, Serial No. 134,335

Term of patent 3½ years

(Cl. D80—2)

To all whom it may concern:

Be it known that I, Alan J. Ragunt, a citizen of the United States, residing at Rockford, in the county of Winnebago, and State of Illinois, have invented a new, original, and ornamental Design for a Serving Bar Top, of which the following is a specification, reference being had to the accompanying drawings, forming part thereof.

In the drawings:

Fig. 2 is an end elevational view thereof, and

Fig. 3 is a perspective view of the rear side of the bar top.

I claim:

The ornamental design for a serving bar top, substantially as shown.

ALAN J. RAGUNT.
